HEAT EXCHANGE DEVICE

John R. Boyle and John R. Boyle, Jr., Chicago, Ill.

Application January 31, 1955, Serial No. 484,952

11 Claims. (Cl. 257—37)

The present invention relates to a heat exchange device, and more particularly to an evaporative condenser type of heat exchange device.

More specifically, the invention aims to provide an improved heat exchange device comprising a vertically disposed helical cooling coil structure disposed above a water tank, and utilizing a motor driven rotary spinner extending downwardly inside the cooling coil structure and provided with centrifugal water lifting means and centrifugal water spraying means to lift the water from the tank and to spray it outwardly against the coil structure.

One of the objects of the invention is to provide an improved coil structure, and an improved method of making the same. This improved coil structure comprises concentrically disposed inner and outer helical coils which are physically held together in fixed concentric spacing by long narrow fin plates which are placed in intervening relation between the inner and outer coils. These fin plates are arranged substantially radially of the inner and outer coils, and are spaced close together to provide as large an area of heat radiating surface as possible. Each fin plate has spaced notches along its inner edge that engage over the convolutions of the inner coil, and has spaced notches along its outer edge that similarly engage over the convolutions of the outer coil. Thus, the inner and outer coils have direct heat radiating contact with the multiplicity of fins, whereby these fins afford a very large area of metallic heat radiating surface, in addition to the surface areas of the coils themselves.

Another object of the invention is to provide an improved construction of rotary spinner which is disposed axially in the center of the above coil structure, and which functions to lift water from the water tank and to project it outwardly by centrifugal force against the coil structure made up of the inner and outer coils and the intervening fins. This improved rotary spinner comprises blades or vanes which radiate outwardly from the central driving axis and which have outer edges that diverge upwardly and outwardly to give a centrifugal force component to the water for lifting it from the tank. The lower portions of the spinner blades have cup-shaped lips formed along their outwardly diverging edges for centrifugally lifting water from the tank below the coil structure. In the preferred construction of spinner, these cup-shaped lips are formed on the back or trailing sides of the blades with respect to the direction of rotation of the spinner, and small water scoops are formed at the bottom ends of these cup-shaped lips to start the water flowing upwardly in the lips. The cup-shaped lips are produced by forming reversely bent flanges along the edges of the blades. At the upper portion of each spinner blade, from which the water is to be projected, the bend of the flange is diminished to a substantially tangentially-shaped lip, which is unable to hold the column of water traveling upwardly in the cup-shaped lip, and hence the water is projected centrifugally from this upper portion of the spinner. This substan-

2

tially tangential lip is preferably crimped or serrated along its edge to give a broad, finely divided spray from the upper portion of the spinner against the upper portion of the coil and fin assembly, the water then cascading down over the lower portion of the coil and fin assembly.

Another object of the invention is to provide the motor driven spinner assembly with an air circulating fan, and with a combined hydraulic balancing and water eliminating device. The air circulating fan is mounted on the spinner shaft above the coil and fin assembly, and produces a forced draft of air flowing through the coil and fin assembly. The combined hydraulic balancing and water eliminating device is also mounted on the spinner shaft above the coil and fin assembly, and functions to catch and trap much of the excess water vapor which is being carried upwardly by the forced draft of air induced by the fan. A part of this accumulation of water is retained in an internal annular lip formed in the device, where this water creates a hydraulic balancing annulus for balancing the spinner and fan assembly against dynamic unbalance.

Other objects, features and advantages of the invention will appear from the following detail description of one preferred embodiment thereof. In the accompanying drawings illustrating such embodiment:

Figure 1 is a vertical axial sectional view through our improved heat exchanging device;

Figure 2 is a transverse sectional view taken on the plane of the line 2—2 of Figure 1;

Figures 3 and 4 are side and end views showing the step of winding the inner coil on a mandrel;

Figure 5 is an elevational view of one of the intervening fins;

Figure 6 illustrates the step of pressing the fins over the inner coil, with the fins extending substantially radially of the coil;

Figure 7 illustrates the step of winding the outer coil over the outer edges of the fins;

Figures 8, 9 and 10 are transverse sectional views of the rotary spinner, taken on the planes of the lines 8—8, 9—9 and 10—10 of Figure 1; and

Figure 11 is a fragmentary edge view of the rotary spinner, showing edge portions corresponding to Figures 8, 9 and 10.

The upper portion of the device is assembled within a sheet metal housing 16, which has a lower end 17 of circular cross-section for attaching to the outer side of the coil and fin assembly. The upper portion of the housing may be of circular cross-section, or of oblong cross-section as shown in Figure 2. Supported in the upper part of the housing 16 by a mounting yoke 18 is a vertically disposed electric motor 20. The downwardly extending shaft 21 of this motor is connected through a flexible coupling 22 to a lower shaft 24 on which are mounted the air circulating fan 25, the combined hydraulic balancer and water eliminator 26, and the rotary spinner 27. The lower end of the shaft 24 seats in a guide bearing 28 secured to the bottom wall of a water tank 30 supported at the lower end of the device.

Surrounding the rotary spinner 27 is the coil and fin assembly 32 comprising the inner tubular coil 34, the outer tubular coil 36, and the circularly arranged group of intervening fin plates 38 disposed between the inner and outer coils. The coil and fin assembly 32 has suitable attachment intermediate its ends to the circular constricted lower end 17 of the housing 16, with the lower end of the assembly extending down into the water tank 30 to a point just above the normal water level in the tank. The fluid to be cooled is circulated through the inner and outer tubular coils 34 and 36, and the rotary spinner 27 is adapted to lift water from the tank 30 and

spray it against the inner and outer coils and against the intervening ring of fins 38. In the case of an evaporative condenser, the fluid which would be circulated through the inner and outer coils 34 and 36 would consist of a gaseous refrigerant received from a compressor or the like.

Referring now to the improved method of making the coil and fin assembly 32, Figures 3 and 4 show the initial operation of winding the inner coil 34 around a rotating mandrel 40. The coil 34 is of a ductile material capable of being wound in this manner about the rotating mandrel 40. After the coil has been thus wound about the mandrel, the sheet metal fins 38 are pressed into position over the coil. One of the fins is shown in side elevation in Figure 5, from which it will be seen that each fin has semi-circular notches 34' in one edge for engaging over the turns of the inner coil 34, and has semi-circular notches 36' in its opposite edge for receiving the turns of the outer coil. The notches 34' are of such dimension that they have a tight pressed fit over the convolutions of the inner coil 34. As shown in Figure 6, successive fins 38 are pressed over the inner coil in uniformly spaced radially extending relation. The successive fins have their notches 34' spaced successive distances along their lengths corresponding to the different linear positions of the convolutions of the inner coil, the same also being true of the outer notches 36'. Following this mounting of the fins on the inner coil, the outer coil 36 is wound around the radially projecting edges of the fins, with the successive turns of the outer coil fitting in the notches 36' in the outer edges of the fins, this latter operation being shown in Figure 7. The outer coil 36 is also of ductile metal capable of being wound around the fins in this manner, the winding thereof being preferably performed while the assembly is still on the mandrel 40. After removal of the coil and fin assembly from the mandrel, the upper ends of the inner and outer coils are connected to an inlet chamber 41 and the lower ends are connected to a liquid receiver 42.

Referring now to the rotary spinner 27, this comprises a long metallic plate of tapering or wedge-shaped outline. Extending centrally of said plate from end to end is a half-round or U-shaped indentation 46 which is secured over the spinner shaft 24. Those portions of the tapering plate which extend outwardly from the shaft 24 constitute diametrically opposite spinner blades or vanes 27a and 27b. Extending upwardly along the lower edge of each spinner blade is a water lifting channel 48 formed by curving the edge of the blade rearwardly into a U-shaped section, as shown in Figure 10. Each water lifting channel 48 is located on the trailing side of its respective vane; i. e. considering the vanes rotating in a clockwise direction, then these water lifting channels 48 are shaped to project counter-clockwise from the edges of their respective vanes. At the lower end of each water lifting channel 48 is formed a water scoop 49, consisting of a tongue or lip of metal curved to extend horizontally from the lower end of the channel 48. Each water scoop faces in a leading direction with respect to the direction of rotation of the spinner; i. e. for a clockwise direction of rotation of the spinner each water scoop faces in a clockwise direction. The lower end of the spinner is submerged below the water level in the tank 30, and hence the water scoops 49 start the upward flow of water through the water lifting channels 48 on the trailing sides of the vanes 27a and 27b. Because of the outwardly diverging angle of the water lifting channels 48, the flow of water continues up to the upper ends of the channels under the action of centrifugal force. Beginning at a point just above the constricted portion 17 of the housing, the lip of metal forming the channel 48 is bent in a trailing direction and is formed with a corrugated or serrated edge to form a water spraying lip 52 extending from the water lifting channel 48 to the top of the spinner. This water spraying lip 52 may have its angle of discharge increase

75

progressively toward the top of the spinner; i. e. the angle subtended between the back side of the vane and the lip 52 may increase toward the top of the spinner. This water spraying lip 52 results in the water being projected from the spinner in a broad finely divided spray over the top half of the coil and fin assembly 32. The excess water cascading down over the coils and fins aids in the cooling of the lower portion of the coil and fin assembly. Attention is directed to the fact that the air is driven off the leading edge of each vane 27a and 27b, and that the water projected from the spraying lip 52 leaves from the trailing edge of each vane. Hence, the water being sprayed is under a slightly negative pressure, which augments break-up of the water particles and evaporation.

Referring now to the combined air deflector, water eliminator and hydraulic balancer, indicated at 26, this device comprises a hollow cone provided with a hub portion 26a which is mounted on the shaft 24. The lower edge of the cone has an inturned flange 26b which forms an annular water collecting trough 26c concentric with the axis of rotation of the shaft 24. The cone is located sufficiently close to the top of the coil and fin assembly 32 to function as an air deflector for deflecting outwardly the air passing up through the center of the coil and fin assembly 32. The fan 25 located above the cone 26 acts to draw a rising column of air upwardly through the coil and fin assembly 32, and the cone 26 functions to deflect the central portion of this rising column of air outwardly from the center of the coil and fin assembly for passage around the edge of the cone. The cone 26 performs its water eliminating function by trapping water particles which are carried upwardly in the central portion of the rising column of air passing upwardly through the coil and fin assembly 32. When the air is deflected outwardly around the periphery of the cone, a substantial proportion of the heavier water particles will continue their upward travel into the cone, from whence the collected water will be spun centrifugally down into the water collecting trough 26c. The annulus of water held centrifugally in this trough 26c functions as a dynamic balancing medium for dynamically balancing the rotary spinner 27. The fan 25 operates in a circular opening 55 formed in a partition wall 56 mounted transversely of the housing 16. The air flow through the device is indicated in Figure 1 by the wavy arrows a, and the water projection from the upper portion of the spinner 27 is indicated by the dash-dot lines w. In our copending application, Serial No. 484,172, filed January 26, 1955, now U. S. Patent No. 2,773,676, issued December 11, 1956, we have illustrated the present heat exchange device employed as an evaporative condenser in a self-contained heating, cooling and ventilating system for house trailers, small homes and the like. In such situation, the apparatus is enclosed in an outer duct or housing which encloses the housing 16 and water tank 30, leaving space for the admission of air up along the sides of the water tank 30.

Because of the very large amount of surface area of the coil and fin assembly 32, afforded by the multiplicity of fins 38, it is possible to operate the unit dry with a high degree of efficiency, particularly if operating in localities where water is scarce. Thus, the condenser can be of dual operating type, functioning either as a sprayed evaporative condenser or as a dry condenser.

Our invention also contemplates modified methods of making the coil and fin assembly 32. For example, the inner and outer coils 34 and 36 may be separately formed by the use of suitable tube bending or tube coiling apparatus and may be thereafter assembled one within the other. Following this, the fins 38 having the notches 34' and 36' formed therein may be introduced flatwise into the space between the coils at one end of the coil assembly, each fin being passed up to the proper longitudinal position, between the coils and being then turned

edgewise to lie radially of the coils, with its notches 34' embracing the convolutions of the inner coil 34 and with its notches 36' embracing the convolutions of the outer coil 36.

While we have illustrated and described what we regard to be the preferred embodiment of the invention, nevertheless it will be understood that such is merely exemplary and that numerous modifications and rearrangements may be made therein without departing from the essence of the invention.

We claim:

1. In a heat exchange device, the combination of a cooling coil, a water tank below said coil, and a motor driven spinner operative to lift water from said tank and to spray it against said coil, said motor driven spinner comprising a plurality of rotating vanes having their lower ends immersed in the water in said tank, each of said vanes having an upwardly and outwardly sloping water lifting trough operative to lift water centrifugally from said tank for spraying it against said coil.

2. In a heat exchange device, the combination of a cooling coil, a water tank below said coil, and a motor driven spinner operative to lift water from said tank and to spray it against said coil, said motor driven spinner comprising a plurality of rotating vanes having their lower ends immersed in the water in said tank, each of said vanes having a water scoop at its lower end and an upwardly and outwardly sloping water lifting trough operative to lift water from said tank for spraying it against said coil.

3. In a heat exchange device, the combination of a cooling coil, a water tank below said coil, and a motor driven spinner operative to lift water from said tank and to spray it against said coil, said motor driven spinner comprising a plurality of rotating vanes having their lower ends immersed in the water in said tank, each of said vanes having an upwardly and outwardly sloping water lifting trough operative to lift water centrifugally from said tank, and including a discharge lip portion at the upper portion of each vane for projecting the water against said coil.

4. In a heat exchange device, the combination of a cooling coil, a water tank below said coil, and a motor driven spinner operative to lift water from said tank and to spray it against said coil, said motor driven spinner comprising a plurality of rotating vanes having their lower ends immersed in the water in said tank, each of said vanes comprising a water scoop at its lower end, an upwardly and outwardly sloping water lifting trough operative to lift water centrifugally from said scoop, and a serrated lip portion at the upper end of each vane for projecting the water against said coil in spray form.

5. In a heat exchange device, the combination of a coil and fin assembly comprising an inner coil, an outer coil and a plurality of fins interposed between said coils, a water tank below said coil and fin assembly, and a motor driven spinner disposed within said inner coil operative to lift water from said tank and to spray it against said coil and fin assembly, said spinner comprising a plurality of rotating vanes having their lower ends immersed in the water in said tank, each of said vanes having an upwardly and outwardly sloping water lifting trough operative to lift water centrifugally from said tank for spraying it against said coil and fin assembly.

6. In a heat exchange device, the combination of a coil and fin assembly comprising vertically disposed inner and outer coils and fins interposed substantially radially between said coils, a water tank below said coil and fin assembly, and a motor driven spinner disposed vertically within said inner coil and operative to lift water from said tank and to spray it against said coil and fin assembly, said spinner comprising a plurality of rotating vanes having their lower ends immersed in the water in said tank, each of said vanes having an upwardly and

outwardly sloping water lifting trough operative to lift water centrifugally from said tank, and each vane including a discharge lip portion adjacent to its upper end for projecting the water against said coil and fin assembly.

7. In a heat exchange device, the combination of a coil and fin assembly comprising vertically disposed inner and outer spaced helical coils and a plurality of sheet metal fins interposed between and extending lengthwise of said coils in substantially radial planes, said fins having notches in their inner and outer edges embracing the convolutions of said inner and outer coils, a water tank below said coil and fin assembly, and a motor driven spinner disposed concentrically within said inner coil and operative to lift water from said tank and to spray it against said coil and fin assembly, said motor driven spinner comprising a plurality of rotating vanes having their lower ends immersed in the water in said tank, each of said vanes having a water scoop at its lower end and having an upwardly and outwardly sloping water lifting trough operative to lift water from said tank for spraying it against said coil and fin assembly.

8. In a heat exchange device, the combination of a cooling coil, a liquid tank below said coil, and a motor driven spinner operative to lift liquid from said tank and to spray it against said coil, said spinner comprising a plurality of rotating vanes having their ends immersed in the liquid in said tank, upwardly and outwardly sloping water lifting troughs on the lower portions of said vanes from lifting liquid centrifugally from said tank, and discharge lips on the upper portions of said vanes for discharging the liquid against said coil, said discharge lips being disposed on the trailing edges of said vanes so that the liquid discharged therefrom is under a negative pressure.

9. In a heat exchange device, the combination of a cooling coil, a liquid tank below said coil, and a motor driven spinner operative to lift liquid from said tank and to spray it against said coil, said spinner comprising a plurality of rotating vanes having their lower ends immersed in the liquid in said tank, a liquid scoop at the lower end of each vane facing in a leading direction with respect to the direction of rotation of said vanes, an upwardly and outwardly sloping liquid lifting trough on the trailing side of the lower portion of each vane for receiving liquid from said scoop and for lifting liquid centrifugally from said tank, and a discharge lip on the trailing edge of the upper portion of each vane for discharging the liquid against said coil.

10. In a heat exchange device, the combination of a cooling coil, a water tank below said coil, a motor driven shaft extending downwardly through said cooling coil into said tank, a spinner on said shaft comprising vanes operative to lift the water centrifugally from said tank and to spray it on said coil, and a combined water eliminating and dynamic balancing device on said shaft above said spinner, said device comprising an inverted bowl rotating with said shaft and adapted to catch upwardly moving water particles, said bowl including an annular internal lip adapted to hold a dynamically balancing ring of water.

11. In a heat exchange device, the combination of a cooling coil, a water tank below said coil, a motor driven shaft extending downwardly through said cooling coil into said tank, a fan on the upper portion of said shaft for inducing an upward flow of air through said coil, a spinner in the lower portion of said shaft comprising vanes operative to lift the water centrifugally from said tank and to spray it on said coil, and a combined air baffle and hydraulic balancing device on said shaft between the upper end of said coil and said fan, said device comprising an air deflecting member operative to deflect the upward flow of air outwardly through the upper

portion of said coil, and including a flange adapted to hold a dynamically balancing ring of water.
